Inventor:

Paul Lungstrass,
by Hugh K. Magne, P.

Attorney.

UNITED STATES PATENT OFFICE.

PAUL LUNGSTRAS, OF ST. LOUIS, MISSOURI, ASSIGNOR TO LUNGSTRAS DYEING AND CLEANING COMPANY, OF ST. LOUIS, MISSOURI, A CORPORATION OF MISSOURI.

CLOTHES-DRYING APPARATUS.

Application filed August 20, 1924. Serial No. 733,240.

To all whom it may concern:

Be it known that I, PAUL LUNGSTRAS, a citizen of the United States, residing at the city of St. Louis, in the State of Missouri, have invented certain new and useful Improvements in Clothes-Drying Apparatus, of which the following is a specification.

This invention relates to the art of drying clothes and the like, and has for its object the provision of an apparatus whereby the drying may be effected without any shrinkage or wrinkling of the clothes. This invention may be employed advantageously in laundries, as well as in cleaning and dyeing establishments. Hitherto, in drying clothes by the old method, more or less shrinkage has occurred, the shrinkage being especially pronounced in the subsequent drying of clothes which have been freshly dyed. In drying by the old methods, considerable wrinkling has, also, occurred, especially along the seams. The present invention minimizes or practically eliminates shrinkage and wrinkling, so that the clothes after drying present a smooth and finished appearance, rendering unnecessary any ironing or pressing except where creasing is customarily resorted to, as for instance, in the pressing of a pair of trousers. The most tedious part of the operation of ironing or pressing consists in the smoothing out of wrinkles, and by means of the present invention the operator is relieved of this burden.

The invention consists generally in providing a hollow dummy form of yieldable material on which the clothes are placed, and which is then inflated to a suitable pressure, and maintained thereat while the clothes are drying.

In the accompanying drawings forming part of this specification, in which like numbers of reference denote like parts wherever they occur,

Figure 1 is a view depicting one embodiment of this invention as employed in drying a pair of trousers; and

Figure 2 is a sectional view on the line 2—2 of Figure 1.

For purposes of illustration, the article to be dried is a pair of trousers 1, which are placed over a hollow dummy form 2, shaped

to fit in the trousers. The form 2 is formed of elastic material, being preferably molded of rubber, having its lower end or the bottom of its legs 3 closed, and its upper or waist end 4 open to facilitate withdrawal of the form 2 from the core on which it is molded. After withdrawal of the form 2 from the core around which it has been molded, the ends 4 may be brought together, and sealed in any suitable manner. The method of sealing adopted in the present instance consists in placing opposing bars 5 over each of the opposing ends 4, and clamping the ends 4 between the bars 5 by means of clamps 6. The means for attaching the bag 2 to a supplier of inflating fluid, such as compressed air, may be embodied in a valve 7, which may be of the well known form such as is attached to the inner tubes of automobile tires, and which may be attached to the bag 2 in the same manner. The valve 7 may be attached to the bag 2 at any suitable point thereon not covered by the trousers, being preferably located at the waist end.

The procedure is as follows. The trousers 1 to be dried are pulled over the deflated form 2 and buttoned. Compressed air is then supplied from any suitable source through the valve 7 to the interior of the form 2, inflating the form 2 and exerting pressure therefrom against the inner sides of the enclosing trousers, producing approximately equal tension on the cloth in different directions. The most suitable air pressure, as determined by experiment, is approximately five pounds to the square inch. The drying operation may be speeded in any suitable manner, as for instance, by the application of heat, by drying in a vacuum, or by a combination of both heat and vacuum drying. The tension is fairly uniformly distributed over the cloth by this method, and wrinkling is prevented. Furthermore, shrinkage is mitigated, or practically prevented, the trousers drying without distortion. The elastic nature of the form 2 and of the fluid within causes the intimate following of the outside surface of the form 2 into the irregularities in the inner surface of the cloth of the trousers, which intimate contact prevents slippage of the trousers on the form while drying.

100
105

It will be manifest that shrinkage in all directions is thus prevented. When the drying operation has been completed, the valve 7 is opened, thus permitting the escape of the air confined in the form 2 and deflating the latter. In the event it is desired to effect a quick and efficient removal of the fluid from the form the upper end 4 thereof may be opened by releasing the bars 5 held by the clamps 6. The trousers may then be removed.

Clothes which have been subjected to the foregoing treatment present a smooth finished appearance, and no ironing is necessary, except where creasing is desired. Furthermore, any glossiness, such as is unavoidably produced by pressing or ironing in the usual way, cannot result from the new method herein set forth. The treatment is mild and the wear on the clothes is, also, less. The pressing of trousers, coats or other garments may, therefore, be better accomplished by a new method of pressing, which consists in the first step of drying the clothes without wrinkling in the foregoing manner, and in the second step of creasing the same, no ironing being necessary except along that portion of the garment where the crease is desired. Of course, different shaped dummy forms will be provided for different kinds of garments.

Having thus described this invention, I hereby reserve the benefit of all changes in form, arrangement, order, or use of parts, as it is evident that many minor changes may be made therein without departing from the spirit of this invention or the scope of the following claims.

I claim:

1. A clothes drying apparatus comprising an inflatable garment-fitting body having one end open, a valve thru which the said body is inflated, and means for sealing the said open end of the body during the period of inflation, said means being removable to open the said end to effect the quick removal

of the inflating medium from the inside of the said body.

2. A clothes drying apparatus comprising a hollow distensible body shaped to fit into and to conform to the garment supported thereon and having one end open; an inlet-valve thru which the said body is inflated, and means for clamping the body together at its said open end to seal the body during the period of inflation, said clamping means being releasable to open the said body at said end to effect the quick removal of the inflating medium from the inside of the said body.

3. A trousers drying apparatus comprising a hollow elastic form shaped to fit into the trousers and having its upper end open, an inlet-valve on said form to permit inflating and deflating thereof, a pair of opposing bars disposed on relatively opposite sides of the form and adjacent the open end thereof, and clamps for securing the bars together to clamp the open end of the said form therebetween and thus seal the opening during the period of inflation, said clamps being releasable to open the form at said end to effect the quick removal of the inflating medium from the inside of the said form.

4. A clothes drying apparatus comprising a hollow distensible body of a shape to fit into and to conform to the garments supported thereon and having a valved member thru which it may be inflated and deflated, said body being provided with a large opening to effect a quick removal of the inflating medium from the inside of the body, and a releasable clamp engaged about the said body adjacent the enlarged opening and being operable for drawing the edges of the opening together to seal the opening during the period of inflation.

In testimony whereof I hereunto affix my signature.

PAUL LUNGSTRAS.
